UNITED STATES PATENT OFFICE

CHARLES L. GEORGE, OF FINDLAY, OHIO, ASSIGNOR TO THE BUCKEYE TRACTION DITCHER COMPANY, A CORPORATION OF OHIO

DIPPER-STICK CONTROL FOR EXCAVATING MACHINES

Application filed March 7, 1931. Serial No. 520,856.

This invention relates to excavating apparatus of the dipper type, and particularly to the control for the dipper-stick.

The object of the invention is the provision, in apparatus of the class described, of an improved cable control for the operating movements of the dipper-stick whereby a more rapid, efficient and powerful working of the apparatus may be accomplished.

10 The invention is fully described in the following specification, and while in its broader aspect it is capable of embodiment in numerous forms, one embodiment thereof is illustrated in the accompanying drawings, in which—

Figure 1 is a side elevation of an apparatus embodying the invention, with one position of the dipper-stick and its dipper shown in full lines and with other positions thereof shown in dotted lines. Fig. 2 is a perspective view of the dipper-stick and its control with parts broken away. Figs. 3 and 4 are sections on the lines 3—3 and 4—4, respectively, in Fig. 1, and Fig. 5 is a diagrammatical view illustrating the connections of the hoist and crowd and the holding cables with the boom and dipper-stick, the boom and dipper-stick being partially shown in dotted lines.

30 Referring to the drawings, 1 designates the customary housing for the operator and operating machinery, which housing is rotatably mounted on a suitable tractor means 2. The usual boom 3 is pivoted to the forward end of the base portion of the housing 1 for vertical pivotal movements relative thereto and such movements are controlled by a cable 4, which extends from a control drum (not shown) within the housing 1 to and 35 around a sheave 5 on the forward end of the boom and thence back to a suitable anchoring point on the housing, shown in the present instance at 6.

The dipper-stick 7, carrying the dipper 8 at its outer end, is slidably mounted on a guide-frame 9, and this frame is mounted on a shipper-shaft 10 carried by the boom for vertical rocking movements relative thereto. The shaft 10 is mounted on the top of the boom substantially midway of its length and

the dipper-stick 7 crosses the boom from front to rear, and the longitudinal movements of the stick are at all times in intersecting relation to the boom axis as well understood in the art. 55

In the present instance, the dipper-stick 7 is composed of two transversely spaced beam members 7^a and 7^b rigidly connected at their ends and forming members with which the frame 9 engages to guide the longitudinal movements of the stick. As this manner of mounting the stick is old, it need not be specifically described.

The control for the dipper-stick 7 comprises the crowd and hoist cable 11 and the holding cable 12 in cooperation with the customary or any suitable operating mechanism therefor in the housing 1, which mechanism includes the two drums 13 and 14 on which said cables respectively wind. It is understood in mechanisms of this character that the control drums for the cables are adapted to be independently and positively driven in cable-winding direction and that their unwinding movements are brake-controlled. 75

The crowd and hoist cable 11 extends forwardly from the control drum 13 around a sheave 15 from the under side thereof, which sheave is mounted on the shaft 10 intermediate the dipper beams 7^a, 7^b, then extends rearwardly around a sheave 16 on a cross shaft 17 at the rear end of the dipper-stick, then forward along the top of the dipper-stick to and around a sheave 18 carried by the forward end thereof, thence upward around a sheave 19 on the forward end of the boom 3, thence down around the forward side of a sheave 20 mounted on the shaft 21 with the sheave 18, thence rearward along the top of the dipper-stick around a sheave 22 on the shaft 17 with the sheave 16, and thence forward along the under side of the dipper-stick to a point where it is anchored to the guide frame 9, as indicated at 23. It is evident that a drawing in of the cable 11 effects a shortening thereof and a consequent outward crowding of the dipper-stick the permissible extent, as hereinafter described, and also effects a hoisting of the dipper-car- 95 100

rying end of the stick, or these movements of the stick may be in unison or alternate, depending on the digging conditions or the resistance offered to the respective movements of the stick.

It is apparent from the above, that the hoist and crowd cable has a single looped connection with the outer end of the boom and that each run of the cable from such 10 connection has looped hoisting connection with the forward end of the dipper-stick and also looped crowding connection with the rear end of the stick, thus providing a two-part hoisting connection between the forward 15 end of the dipper-stick and the upper end of the boom, and a four-part crowding connection with the rear end of the stick. This provides a very efficient and powerful hoisting and crowding connection of the 20 cable with the dipper-stick.

The holding cable 12 extends forward from its control drum 14 under a small guide sheave 24 carried by a bracket arm 25 projecting down from the rear end of the dipper-stick, thence over a guide sheave 26 on the shaft 10 and forward along the stick to near the forward end thereof where it passes around a sheave 27 and thence back along the stick to the guide frame 30 9 to which it anchors as at 28. The sheave 27 is mounted between the beams of the dipper-stick on a shaft 29, and the sheaves 15, 16, 22 and 26 are also mounted between the dipper beams. The sheaves 18 and 20, 35 however, are mounted between side brackets 30, which rise from the forward end of the dipper-stick in transversely spaced relation and carry the shaft 21.

It is apparent that a shortening of the 40 cable 12 will effect a rearward sliding of the dipper-stick 7 on the guide frame 9, if the cable 11 is free to pay out to permit such movement, and that when the cable 12 is held against paying-out movement, it 45 forms a holding or anchoring means for the dipper-stick to prevent a lengthwise outward movement thereof, and will permit it to freely swing about the shaft 10 as an axis.

When the crowd and hoist cable 11 is shortened or drawn in by winding action of its 50 drum 13, it will first effect an outward movement of the dipper-stick to the limit permitted by the holding cable 12 and will then raise the outer end of the dipper-stick toward the upper end of the boom. This movement 55 may be continued until stopped by the sheaves 18 and 20 on the dipper-stick striking the sheave 19 on the boom. When such sheaves strike and the pull on the cable is continued, the stick and its dipper move substantially 60 from the full line position to the upper dotted line position shown in Fig. 1, the sheaves 18 and 20 traveling partially around the sheave 19 ordinarily in contact therewith during 65 such movement. It is desirable to prevent

such contact of the sheaves and this is accomplished by extending the outer end of the brackets 30 beyond the sheaves 18 and 20, and providing a segmental plate 31 on the shaft with the sheave 19, at each side thereof, in position to have peripheral stop engagement with the outer rounded surfaces of the brackets 30. When the brackets 30 strike the segments 31, they cause the latter to swing forward and upward and to have 70 75 rolling contact with the brackets.

It is apparent that I provide a control for the movements of the dipper-stick which imparts a powerful crowding and hoisting movement to the dipper-stick for excavating and load-hoisting purposes due to the number of runs of the cable backward and forward on the stick, and, so far as I am aware, enables a more rapid and efficient operation of the stick than is possible with the controls 80 85 heretofore used.

I wish it understood that my invention is not limited to any specific construction, arrangement or form of the parts, as it is capable of numerous modifications and changes 90 without departing from the spirit of the claims.

Having thus described my invention, what I claim as new and desire to secure by United States Letters Patent is:

1. In an apparatus of the class described, a boom having a sheave at its outer end, a dipper-stick having a sheave at its outer end, a crowd and hoist cable for the dipper stick, coacting guard parts carried by said boom and dipper-stick to have coaction with each other and prevent contact of said sheaves when the dipper stick is raised, one of said parts being pivotally mounted and having rolling coaction with the other part. 105

2. In an apparatus of the class described, a boom, a dipper stick carried by the boom for vertical rocking and longitudinal reciprocatory movements relative thereto, control means for the stick to impart rocking and longitudinal reciprocatory movements thereto, a guard plate on the top portion of the dipper-stick adjacent to its outer end and having a rounded outer surface, and a segmental plate pivotally carried by the outer end of the boom and adapted to coact with said guard plate to limit the raising movements of the stick relative to the boom and to have rolling coaction therewith. 115

In testimony whereof I have hereunto signed my name to this specification.

CHARLES L. GEORGE.
